(57) CLAIM

The ornamental design for a scalp massaging shampoo brush, as shown and described.

DESCRIPTION

FIG. 1 is a front elevational view of a scalp massaging shampoo brush showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a perspective view thereof; and,
FIG. 8 is a second perspective view thereof.
The broken lines illustrate portions of the scalp massaging shampoo brush that do not form part of the claimed design.
